UNITED STATES PATENT OFFICE.

PRESTON MYERS, OF DETROIT, MICHIGAN.

VEHICLE-SIGNAL.

1,364,130.

Specification of Letters Patent. Patented Jan. 4, 1921.

Application filed November 15, 1919. Serial No. 338,369.

To all whom it may concern:

Be it known that I, PRESTON MYERS, a citizen of the United States of America, residing at Detroit, in the county of Wayne 5 and State of Michigan, have invented certain new and useful Improvements in Vehicle-Signals, of which the following is a specification, reference being had therein to the accompanying drawings.

- 10 The invention relates to vehicle signals and has for one of its objects the provision of signals at both the front and rear of a vehicle which are adapted to be actuated by vacuum. Another object is the provision 15 of a controlling means which is so arranged that upon actuation of the front signal the rear signal will also be actuated to display a designation. A further purpose is to provide a construction in which the means for 20 actuating the indicator has limited movement so that the designations upon the indicator will always be correctly shown when the indicator is actuated. Other objects reside in the novel combinations and 25 arrangements of parts as more fully hereinafter set forth.

In the drawings:

Figure 1 is a diagrammatic view of the construction embodying my invention;

- 30 Fig. 2 is a side elevation, with part of the casing broken away, of a signal;

Fig. 3 is a top plan view thereof, with part of the casing broken away;

- Fig. 4 is a cross section on the line 4—4 35 of Fig. 3;

Fig. 5 is an end view, with the end of the casing removed.

- 1 and 2 are, respectively, the rear and front signals upon a vehicle, such as an 40 automobile, which are respectively connected by the pairs of tubes 3 and 4 to a valve-controlled vacuum chamber 5, which is in communication with the intake manifold 6 of an internal combustion engine 45 through the tube 7. The rear signal 1 has the two designations "Turn" and "Stop," and the front signal 2 has the two designations "Right" and "Left." The tubes 3 and 4 are each controlled by the valves 8, 50 which have the stems 9 extending through the vacuum chamber 5 and adapted to be actuated by means of the buttons 10.

- 55 Since both the front and rear signals are constructed alike but one signal (the rear signal) will be described. 11 is a cylindrical casing having a suitable elongated aper-

ture 12 through which the designations may be seen. 13 are suitable ends removably secured upon the casing 11. 14 is a support preferably formed of a sheet metal 60 stamping, this support being secured at its opposite ends to the casing 11, and having struck out ears or projections 15, 16 and 17. 18 is a rotatable indicator within the casing 11 and non-rotatably secured upon the shaft 65 19, which is rotatably mounted in the ears or projections 15, this shaft being substantially axially arranged within the casing. 20^a is a pinion non-rotatably mounted on the shaft 19 near one end thereof. The rotatable indicator 18 is normally held in position, such that its pair of designations can not be seen through the aperture 12 in the casing 11, this position being called the neutral position. When the indicator is rotated in either direction from neutral, one of the designations will be shown through the opening.

For actuating the indicator 18 the following construction is provided: 20 and 21 are 80 collapsible adjacent bellows separated by a partition 22, which is suitably secured to the support 14. 23 and 24 are, respectively, outer walls for the bellows 20 and 21. 25 is a pinion rack having the teeth 26 in mesh 85 with the teeth 27 of the pinion 20^a and having the laterally bent ends 28 secured to the walls 23 and 24 of the bellows, the arrangement being such that when one wall moves toward the intermediate wall 22 the 90 other wall moves away therefrom. For retaining the pinion rack 25 and also the indicator 18 in neutral position the pinion rack has the centrally located depending lug 95 29 which is engaged upon opposite sides by the coil springs 30, the opposite ends of which abut against the struck out ears or projections 16 of the support 14. 31 is a rod for supporting the coil springs 30.

A tube 3 connects into each of the bellows 20 and 21. 100

As thus far described, in operation, by pressing upon either of the buttons 10 for actuating the valves 8 controlling the tubes 3, a tube 3 will be placed in communication 105 with the intake manifold 6 of the engine, thereby placing the bellows in communication with that tube under vacuum, so that the same will collapse, and in collapsing will move the pinion rack 25 and the other bellows with it. This pinion rack rotates the pinion 20^a, which in turn rotates the 110

indicator 18 through the shaft 19. The designations upon the indicator are located to either side of the portion of the indicator normally seen through the aperture 5 12 in the casing, such that they will be correctly shown through the opening in the casing when the indicator is actuated by the bellows, since the movement of the bellows is limited due to the intermediate partition 22.

For the purpose of actuating the rear indicator to disclose that the driver is about to turn, simultaneously when the front is actuated, the buttons 10 for actuating the 15 valves 8 controlling the tubes 4 leading to the front indicator overlap the buttons 10 controlling the actuation of the rear indicator to designate "Turn," so that upon operation of either button to actuate the 20 front indicator to designate "Right" or "Left" the designation "Turn" upon the rear indicator will be simultaneously disclosed.

For the purpose of actuating the rear signal to disclose that the driver is about to stop, one of the buttons 10 for actuating the valves 8 controlling the tubes 3 leading to the rear indicator is actuated, the signal "Stop" will appear, and having no connection with the front indicator the "Stop" signal only will appear, leaving the front indicator neutral.

For driving at night the indicators will be illuminated by the electric lights 32 35 mounted upon the projections or ears 17 of the support 14, these lights using energy from the storage battery.

What I claim as my invention is:

1. In a vehicle signal, the combination 40 with an indicator, of a pair of bellows mechanically connected to said indicator for actuating the same in opposite directions, and means for connecting said bellows to a source of vacuum.
- 45 2. In a vehicle signal, the combination with a rotatable indicator, of a pair of bellows for rotating said indicator in opposite directions, tubes connecting into said bel-

lows and adapted to be connected to a source of vacuum and valves controlling 50 said tubes.

3. In a vehicle signal, the combination with a rotatable indicator provided with a shaft and a pinion upon said shaft, of a pair of adjacent bellows, a rack connected 55 to the opposite sides of said bellows and intermeshing with said pinion and tubes connecting into said bellows and adapted to be connected with a source of vacuum.

4. In a vehicle signal, the combination 60 with a rotatable indicator provided with a shaft and a pinion rotatably secured upon said shaft, of a pair of adjacent bellows, a rack intermeshing with said pinion and secured to the opposite sides of said bellows, 65 means for yieldably maintaining said rack in central or neutral position, and means for connecting said bellows with a source of vacuum.

5. In a vehicle signal, the combination 70 with a casing provided with an aperture, of a rotatable indicator pivotally mounted in said casing and provided with a shaft, a pinion mounted upon said shaft, a pair of bellows adapted to be connected to a source 75 of vacuum, and a rack intermeshing with said pinion and connected to said bellows.

6. In a vehicle signal, the combination with a casing and a support in said casing, of a rotatable indicator pivotally mounted 80 upon said support, a pinion for rotating said indicator, a pair of bellows adapted to be connected to a source of vacuum, a rack intermeshing with said pinion and connected to said bellows, and means for yield- 85 ably retaining said rack in central or neutral position.

7. In a vehicle signal, the combination with a casing provided with an aperture, of a rotatable indicator within said casing, 90 and a pair of bellows within said casing and mechanically connected to said indicator, to actuate the same in opposite directions.

In testimony whereof I affix my signature.

PRESTON MYERS.
